UNITED STATES PATENT OFFICE.

ALBERT L. WYMAN, OF PATERSON, NEW JERSEY.

CUT-OUT.

Application filed June 26, 1922. Serial No. 570,887.

To all whom it may concern:

Be it known that I, ALBERT L. WYMAN, a citizen of the United States, residing at Paterson, in the county of Passaic and State of New Jersey, have invented certain new and useful Improvements in Cut-Outs, of which the following is a specification.

The present equipment for cutting off the current derived from a conductor exterior of a building, as the wire from the aerial of a wireless outfit, from a conductor within the building containing the instrument to be operated is an ordinary knife-switch requiring the operator to go outside of the building in order to operate it. My invention contemplates a cut-out which may be operated with entire facility and reliability from the inside of the building and which will further comply with all the requirements of insurance underwriters and will be extremely simple and compact in construction, inexpensive to manufacture and capable of being installed without greater difficulty than attends the simple operations of drilling a hole through the wall, passing certain parts therethrough and securing the base of the cut-out in position by screws.

In the drawings,

Fig. 1 is a vertical sectional view of a building wall showing the improved cut-out in position, said cut-out appearing partly in side elevation and partly broken away;

Figs. 2 and 3 are horizontal sectional views on lines 2-2 and 3-3, Fig. 1;

Fig. 4 shows in side and end elevation a certain tubular insulating member; and

Fig. 5 shows in side elevation, partly broken away, and in transverse section, a modified form of said member.

Let *a* in Fig. 1 designate the wall of a building. A hole *b* is bored therethrough for the reception of a certain fixed part *h* to be referred to.

A mounting for certain parts is provided as follows: There is an elongated insulating block or base *c* which is attached to the exterior of the wall *a* by screws *d* and which has projecting therefrom about midway its length a forked post *e*, which in the present instance is a separate insulating part secured to the base by screws *f*, the slit or jaw of the fork extending lengthwise of the base and preferably having a metallic wear-piece or lining *f'*. In the base is tapped a hole *g* into which is screwed the threaded end of a

tubular member *h* which fits the hole *b* in the wall *a*. This member has parallel with its bore *h'* a longitudinal passage which may either be a groove *h*² therein (Fig. 4) or a hole *h*³ having its ends turned laterally (Fig. 5). It protrudes at the inside of the wall *a* and on its inner end may be secured by the screw *i* the escutcheon *j*. Fixed to the base *c* by screws *k* on opposite sides of the post *e* are metal clips *l* and *m* of the jaw type forming contacts or terminals; their jaws are arranged in the same plane as the jaw of the fork in the post *e*.

In the jaw of the post *e* on a screw *n* having a clamping nut *o* is fulcrumed between its ends a metal lever *p* the respective ends of which are adapted to enter or clear the corresponding clips *l* and *m* when the lever is moved back and forth on its fulcrum.

This lever is adapted to be operated by a thrustwise movable stem or rod constructed as follows: The body *q* of the rod is preferably composed of insulating material, as hard rubber, and it has embedded in one end the threaded extension piece *r* onto which is screwed the fork *s* which receives in its jaw the lever *p*, a pivotal connection between them being afforded by the screw *t*. The rod extends through the bore *h'* of the member *h* and it has secured on its inner end the handle or knob *u*. The rod is adapted to slide longitudinally through member *h* and its length for this purpose is sufficient to allow the lever to move from engagement with the clip *l* to engagement with clip *m*.

A is the exterior conductor leading from the aerial or other energy source either to a suitable binding post *v* on the end of lever *p* adjoining clip *l* or to the screw *n* which may act as a binding post by having a binding nut *w*. *B* is the grounded conductor suitably electrically connected with clip *m*. *C* is the service conductor which extends from the clip *l*, with which it is suitably electrically connected, along and in a groove *x* (Fig. 2) formed in the back of base *c*, then through the wall *a*, being there housed in the passage of the tubular member *h* (to wit, groove *h*² in Fig. 4 or hole *h*³ in Fig. 5), and finally through a hole *j'* in the escutcheon *j* to and through the instrument *D* to be operated to ground; if desired, the conductor *C* may be in sections connected by the binding post *y*. When the member *h* has the hole *h*³ therein the usual practice will be to embed

the contained part of conductor C in said member when molding the same.

The operation of the device will be understood: When the handle or knob u is pulled inwardly the conductors A and C are electrically connected and conductors A and B disconnected, so that the current passes through the instrument D. When the handle is pushed outwardly the conductors A and B are connected, so that A is grounded, and conductor C is cut out. I have by the instrument described made it possible by a simple thrust movement, entailing simplicity of construction and little alteration of the building wall, to effect the connection or disconnection of a leading-in conductor (as A—C) without leaving the building and so as, at the same time, to provide an ample gap, when the connection is disestablished, between the disconnected parts of the conductor. And by employing a lever fulcrumed between its ends I have made it possible to retain these advantages in a cut-out which includes provision for connecting with or disconnecting from ground the conductor leading from the energy source, as conductor A, when the instrument is put out of or in service.

Having thus fully described my invention, what I claim as new and desire to secure by Letters Patent is:—

1. In a means for electrically connecting and disconnecting from one side of a wall conductors one of which is at the other side of the wall, the combination of a mounting adapted to be secured to the wall at said other side thereof and having a projecting part adapted to extend into the wall, a lever fulcrumed in the mounting and movable back and forth to establish and disestablish electrical connection of the conductors, and means to move the lever on its fulcrum including a sliding member adapted to penetrate the wall and guided in and by said part.

2. In a means for electrically connecting and disconnecting from one side of a wall conductors one of which is at the other side of the wall, the combination of a mounting

including a base adapted to be secured to the wall at said other side thereof and a projecting part detachably secured to said base and adapted to extend into said wall, a lever fulcrumed in the mounting and movable back and forth to establish and disestablish electrical connection of the conductors, and means to move the lever on its fulcrum including a sliding member adapted to penetrate the wall and guided by said part.

3. In a means for electrically connecting and disconnecting conductors one of which is at one side of a wall and the other of which extends through said wall, the combination of a mounting adapted to be secured to the wall at said side thereof and having a projecting part adapted to extend into the wall, said part having a passage for housing the portion of the second-named conductor which extends through the wall, a lever fulcrumed in the mounting and movable back and forth to establish and disestablish electrical connection of the conductors, and means to move the lever on its fulcrum including a sliding member adapted to penetrate the wall and guided in and by said mounting.

4. In a means for electrically connecting and disconnecting conductors one of which is at one side of a wall and the other of which extends through said wall, the combination of a mounting including a base adapted to be secured to the wall exteriorly thereof and a member having a passage therein and detachably secured to the base and adapted to extend into said wall and to house in its passage the portion of the second-named conductor which extends through the wall, a lever fulcrumed in the mounting and movable back and forth to establish and disestablish electrical connection of the conductors, and means to move the lever on its fulcrum including a sliding member adapted to penetrate the wall and guided in and by said mounting.

In testimony whereof I affix my signature.

ALBERT L. WYMAN.
